(57) **CLAIM**

The ornamental design for a gauge module as shown and described.

DESCRIPTION

FIG. 1 is a perspective view of an embodiment of the claimed design of a gauge module;

FIG. 2 is a top view of the gauge module of FIG. 1;

FIG. 3 is a bottom view of the gauge module of FIG. 1;

FIG. 4 is a left side view of the gauge module of FIG. 1;

FIG. 5 is a right side view of the gauge module of FIG. 1, the left side view being a mirror image thereof; and

FIG. 6 is a bottom view of the gauge module of FIG. 1;

FIG. 7 is a bottom view of the gauge module of FIG. 1;

FIG. 8 is a perspective view of an additional embodiment of the claimed design of a gauge module;

FIG. 9 is a top view of the gauge module of FIG. 8;

FIG. 10 is a bottom view of the gauge module of FIG. 8;

FIG. 11 is a left side view of the gauge module of FIG. 8;

FIG. 12 is a right side view of the gauge module of FIG. 8, the left side view being a mirror image thereof;

FIG. 13 is a bottom view of the gauge module of FIG. 8; and,

FIG. 14 is a bottom view of the gauge module of FIG. 8. The broken lines portions of the figures are for the purpose of illustrating portions of the gauge module that form no part of the claimed design.

1 Claim, 10 Drawing Sheets
